CAN OPENER

George W. Marvin, Richton Park, Ill.

Application February 6, 1956, Serial No. 563,607

2 Claims. (Cl. 220—52)

This invention relates to new and useful improvements in can openers, and in particular the invention concerns itself with an opener for cans and other similar containers having a lid or cover connected to their body portion by a perimetrically extending tear strip or band.

In conventional practice, a slotted key is usually furnished with such cans, the same being adapted to have one end of the tear strip inserted in the slot thereof so that when the key is rotated the strip is torn from the can and wound around the key as the latter travels around the perimeter of the can to separate the lid or cover from the main body portion.

The tear strip removed from the can has very sharp edges and the operator's fingers are frequently injured while holding and manipulating the key during winding of the strip thereon. Moreover, if the key is not firmly and properly held, the tear strip winds unevenly and often breaks before the full length thereof is removed from the can, with the result that considerable difficulty is experienced in attempting to complete the opening operation.

The principal object of this invention is to eliminate the above outlined disadvantages incident to the use of conventional openers, this being attained by the provision of means whereby once the end of the tear strip is engaged with a rotatable spindle of the opener, the tear strip may be easily and efficiently wound around the spindle without any danger of the operator's fingers coming in contact with the sharp edges of the tear strip.

Another important object of the invention resides in the provision of means for easily and conveniently removing the wound tear strip from the spindle so that the opener may be repeatedly employed on one can after another, the removal of the wound tear strip from the spindle also being effected without the necessity of touching the strip.

Another important object of the invention is to provide means for locking the spindle in the handle of the opener while the spindle is being rotated to wind the tear strip thereon, the locking means being readily releasable so that the spindle may be conveniently removed from the handle to permit simultaneous removal of the wound tear strip from the spindle.

In accordance with the invention, a split spindle is employed to receive the free end of the tear strip preparatory to winding, and another feature of the invention resides in the provision of means for preventing the split portion of the spindle from collapsing as well as for maintaining the split in the spindle of a proper width in the event that the split portion has been accidentally squeezed together while the spindle was separate from the handle.

With the foregoing more important objects and features in view and such other objects and features as may become apparent as this specification proceeds, the invention resides in the arrangement of parts and details of construction substantially as shown in the accompanying drawing, wherein like characters of reference are employed to designate like parts and wherein:

2

Figure 1 is a side elevational view of the invention, also showing a portion of the can in dotted lines;

Figure 2 is a horizontal sectional view, taken substantially in the plane of the line 2—2 in Figure 1;

Figure 3 is a vertical sectional view, taken substantially in the plane of the line 3—3 in Figure 1; and

Figure 4 is a fragmentary group perspective view of the invention on an enlarged scale.

Referring now to the accompanying drawing in detail, 10 the can opener is designated generally by the reference numeral 10 and embodies in its construction an elongated, substantially cylindrical handle 11, one end portion of which may be increased in diameter to form a convenient hand grip 12, which is preferably formed with a knurled 15 surface 13, as will be clearly apparent.

The other end of the handle 11 is provided with a fork 14 including an upper furcation 14a and a lower furcation 14b. As is best shown in Figures 3 and 4, the upper furcation 14a is provided with an aperture constituting a bearing 15, while the lower furcation 14b has a thickened 20 outer end portion 14c provided with a cup-shaped socket 16 which is coaxial with the aforementioned bearing 15. An upright pin 17 is pressed in a blind bore 18 formed in the portion 14c at the bottom of and coaxially with the 25 socket 16, the pin 17 projecting somewhat above the upper surface of the furcation 14b, as illustrated.

A spindle designated generally by the reference numeral 19 is removably and rotatably mounted in the fork 14 of the handle 11, this spindle including a cylindrical 30 upper body portion 20 and a downwardly tapered lower portion 21 which is provided with a split or slot 22 open at its lower end. The formation of this split divides the lower portion 21 of the spindle into a pair of transversely spaced side portions 21a.

When the spindle 19 is mounted in the fork 14 of the handle 11, it extends slidably and rotatably through the bearing 15 and the split lower end of the spindle is rotatably and removably seated in the aforementioned socket 16. This arrangement prevents the spindle from sliding 35 too far downwardly through the fork and assures that the split portion of the spindle is disposed between the furcations 14a and 14b. As is best shown in Figures 1 and 3, when the spindle is in position in the fork, the aforementioned pin 17 is disposed between the side portions

40 21a of the split lower portion of the spindle and thereby prevents the side portions from collapsing or being squeezed together. In addition, the pin 17 also serves to center the lower end portion of the spindle in the socket 16.

45 The spindle 19 is provided at its upper end with a cross bar 22 having formed intermediate its ends an aperture 23 into which a diametrically reduced upper end portion 19a of the spindle is pressed in a relatively non-rotatable manner. A suitable finger knob 24 is rotatably mounted upon a screw 25 threaded into an aperture 26 formed in one 50 end portion of the cross bar, whereby the spindle 19 may be conveniently rotated. The screw 25 is provided with a lock nut 27 engaging the underside of the cross bar, as shown.

55 60 Means are provided for releasably locking the spindle in the fork 14 of the handle, these means comprising a locking lever 28 which is pivotally mounted by a suitable screw 29 on the upper surface of the furcation 14a, the screw 29 extending through an intermediate portion of the lever and the latter being provided at one end with an upwardly offset portion constituting a finger-piece 30. The other end portion of the lever 28 is also upwardly offset to provide a locking detent 31 which is engageable with an annular groove 32 formed in the body portion 20 of the spindle 19, when the lever 28 is substantially parallel to the longitudinal axis of the handle 11. In this position, as is best shown in Figure

70

2, the lever 28 is prevented from rotating further counter-clockwise by a downturned lug 33 provided at one side of the lever adjacent the screw 29 and abutting the adjacent side of the upper furcation 14a. However, the lever 28 may be rotated in a clockwise direction so that the detent 31 is withdrawn from the groove 32, whereupon the entire spindle 19 may be withdrawn axially in an upward direction from the fork 14.

When the invention is placed in use, the spindle 19 is assembled in the fork 14 and the lever 28 is moved 10 to its locking position so as to retain the spindle in place. Thereupon, the free end of the tear strip 34 of a can 35 is inserted in the split portion of the spindle, that is, between the spindle portions 21a as indicated at 36 in Figure 1.

The handle 11 is then firmly held by the hand grip 12 so that it is disposed substantially tangentially to the can, with the fork 14 engaging the side of the can, as shown in Figure 2. When the spindle 19 is rotated by the cross bar 22 and knob 24, the tear strip 34 will be wound around the split portion of the spindle between the furcations 14a, 14b.

When the tear strip is fully removed from the can upon completion of the opening operation, the wound strip may be removed from the spindle by simply moving the locking lever 28 to its unlocked position and withdrawing the spindle 19 upwardly from the fork 14. During this action the wound tear strip will come in contact with the underside of the upper furcation 14a and will be forced thereby to slide off the spindle, with the end of the strip anchored in the split of the spindle sliding out through the open lower end of the split. It will be apparent from the foregoing that in this manner the tear strip need not be touched by the fingers throughout the entire operation once the end of the strip is inserted in the spindle preparatory to winding. Thus, any possible injury by fingers coming in contact with the sharp edges of the strip is completely eliminated.

It is to be also noted that the taper of the split portion of the spindle will materially assist in withdrawal of the spindle from the wound strip, and once the strip is removed, the spindle may be again assembled in the fork of the handle in readiness for the next can opening operation.

Inasmuch as the free end of the tear strip usually lies flat against the side wall of the can, it is necessary to bend the same outwardly from the can wall before it can be inserted into the split spindle. This operation is customarily performed by grasping the end of the strip with finger nails and injury is often sustained. To eliminate this disadvantage, the outer end of the hand grip 12 is provided with a relatively flat, longitudinally projecting prying tool 37 having a sharp outer edge 38 and an open-ended slot 39 into which the free end of the tear strip 55

may be inserted for bending outwardly from the can wall preparatory to insertion thereof in the spindle 19.

While in the foregoing there has been described and shown the preferred embodiment of the invention, various modifications may become apparent to those skilled in the art to which the invention relates. Accordingly, it is not desired to limit the invention to this disclosure and various modifications may be resorted to, such as may lie within the spirit and scope of the appended claims.

What I claim as new is:

1. An opener for cans having a perimetric tear strip, said opener comprising a handle provided with a fork, a split spindle rotatably and removably mounted in the fork, means for rotating said spindle, said spindle being adapted to have the tear strip of a can wound thereon and to be axially withdrawn from the wound strip during removal of the spindle from said fork, means for locking the spindle in the fork, and means for preventing the split portion of the spindle from collapsing comprising a pin provided in said fork and disposed in the split of the spindle when the latter is positioned in the fork.

2. An opener for cans having a perimetric tear strip, said opener comprising an elongated handle, a fork provided at one end of said handle and having upper and lower furcations, the upper furcation of said fork being formed with an aperture constituting a bearing, the lower furcation of said fork being provided with a socket coaxial with said bearing, a spindle removably positioned in said fork and including an upper body portion disposed above said upper furcation and a lower portion extending slidably and rotatably through said bearing, the lower end of the lower portion of said spindle being rotatably and removably received in said socket, means at the upper end of the spindle for rotating the same, the lower portion of the spindle being provided with a transverse split open at its lower end and adapted to receive the tear strip of a can for winding the same around the portion of the spindle between the furcations of said fork, said spindle being removable axially from the fork and from a strip wound thereon, and means for locking the spindle in said fork, and means for preventing the split lower portion of said spindle from collapsing, said means comprising a pin provided in said socket and disposed axially in the split of the spindle when the latter is positioned in said fork.
